ATTORNEYS

UNITED STATES PATENT OFFICE.

RAY ALAN VAN CLIEF, OF BUFFALO, NEW YORK.

LABEL.

1,349,396.

Specification of Letters Patent. Patented Aug. 10, 1920.

Application filed October 18, 1919. Serial No. 331,648.

To all whom it may concern:

Be it known that I, RAY A. VAN CLIEF, a citizen of the United States, and a resident of Buffalo, in the county of Erie and State 5 of New York, have invented a new and Improved Label, of which the following is a full, clear, and exact description.

This invention relates to improvements in labels and more particularly to poison 10 labels for bottles or other containers, an object of the invention being to provide a label of improved construction having luminous letters which can be readily distinguished at night.

15 A further object of the invention is to provide a label which will obviate accidents, such as are caused by persons in the dark taking poison unintentionally.

20 A further object is to provide a label which can be attached to any bottle or container and which is so constructed that the luminous paint or other material forming the letters is entirely inclosed and protected from the air so that it will retain its 25 luminous qualities for an indefinite period.

With these and other objects in view the invention consists in certain novel features of construction, and combinations and arrangements of parts, as will be more fully 30 hereinafter described and pointed out in the claim.

In the accompanying drawings—

Figure 1 is a view illustrating my improved label on a bottle;

35 Fig. 2 is a perspective view of the label, and

Fig. 3 is a view in section on the line 3—3 of Fig. 1.

My improved label comprises two sheets 1 and 2 both of celluloid or similar transparent material which has the quality of adhesion when subjected to a temperature. On the outer face of the inner sheet 2 the letters 3 of luminous paint spelling out the word poison are located. The outer sheet 40 1 is then placed over the letters and the two sheets are caused to coalesce. This action may be brought about in various ways but its result is to cause the adjacent surfaces of the sheets to adhere to each other so that 50 they form, in effect, a single sheet of celluloid and effectively inclose the letters so that the latter are not subjected to the action of the air and will retain their luminous qualities for an indefinite period. 55

The label may, of course, be fixed to the bottle or container in any desired manner.

I claim:

As a new article of manufacture, a relatively thin, light, flexible, and luminous 60 poison label for bottles and the like adapted to be secured to a poison holding container, said label comprising two sheets of celluloid, letters of luminous material located on the outer face of the inner sheet, 65 and said contacting surfaces of said sheets coalesced confining the material of the letters and forming in effect a single flexible transparent label.

RAY ALAN VAN CLIEF.
